UNITED STATES PATENT OFFICE.

WILLIAM D. MACKRILL, OF FRESNO, CALIFORNIA.

GRADING OR SEPARATING MACHINE.

1,173,366.

Specification of Letters Patent. Patented Feb. 29, 1916.

Application filed June 9, 1915. Serial No. 33,118.

To all whom it may concern:

Be it known that I, WILLIAM D. MACKRILL, a citizen of the United States, residing at Fresno, in the county of Fresno and State 5 of California, have invented certain new and useful Improvements in Grading or Separating Machines, of which the following is a specification, reference being had to the accompanying drawings.

10 My present invention relates broadly to new and useful improvements in grading or separating machines, of the type which are employed in separating the constituents of loose materials in bulk into desired grades, 15 and has particular reference to the provision of a machine of this general character which is especially designed and adapted for use in grading olives.

One of the leading objects of the invention 20 is to construct an olive separator in which a mixture of olives ranging in size from extremely small ones to the large and choice fruit may be graded in such manner, by a number of independent grading sections, that the largest and choicest grade of 25 the fruit will be first removed from the mixture, the next largest and consequently the next choicest grade next removed from the mixture, and so on until each separate grade 30 has been removed and nothing but the refuse and those olives which are too small for commercial purposes remain in the mixture.

A more specific object of the invention is 35 to provide an olive grader consisting broadly in a number of independent sets of grading rollers, each set being adapted to remove from the mixture of olives, one particular grade, and to associate with the several grading sections, a plurality of independent 40 discharge conveyers which serve to remove from the machine into suitable receptacles, each grade of olives.

In connection with the above stated objects, the present invention aims to provide 45 a single conveyer belt which is common to all of the grading sections and is so mounted in the machine that it is adapted to receive from each section, the mixture which passes therethrough and to convey this mixture on 50 to the next grading section.

A further object is to construct the grading 55 rollers in such manner that while they will efficiently perform the function of removing from the mixture all olives of a certain grade, they will not, in so doing, bruise either the olives of the grades which

they remove or the remaining grades which pass through the section, as a mixture.

A further object of the invention is to so construct the grading rollers that they 60 act not only to remove from the mixture all olives of a certain grade, but also serve to convey those olives which they separate from the mixture into a receiving trough.

A concluding object of the invention and 65 one of equal importance with the foregoing, is to construct a machine which is capable of obtaining all of the objects above stated, but nevertheless is simple in construction, and is therefore, capable of being manufactured 70 and operated at a relatively low cost.

The above, and other incidental objects 75 of a similar nature, which will be herein-after more specifically treated are accomplished by such means as are illustrated in the accompanying drawings, described in the following specification, and then more particularly pointed out in the claims which are appended hereto and form part of this application.

With reference to the drawings, wherein 80 there has been illustrated the preferred embodiment of this invention, as it is reduced to practice, and throughout the several views of which similar reference numerals 85 designate corresponding parts, Figure 1 is a top plan view; Fig. 2 is a side elevation; Fig. 3 is a longitudinal section taken medially and vertically through the machine; Fig. 4 is a detail view in transverse section, 90 diagrammatically illustrating the manner in which the worm rollers and cylinders of each grader section act to separate the grade of olives; Fig. 5 is a detail view, diagrammatically disclosing the manner in which 95 the worm roller actuating shafts of the machine and the feed belt are driven from a common power source; Fig. 6 is a detail view in longitudinal section of one of the worm rollers; and Fig. 7 is a detail view 100 disclosing the manner in which the discharge troughs and feed belt are associated in each grader section.

The preferred embodiment of the invention, which is best shown as an operative entirety in Fig. 1 of the drawings, consists broadly in a supporting structure; a plurality of graders which are mounted therein; a feed belt which is so related to the several graders that it will convey the mixture 110 of olives of different sizes which passes through the first grader on to the second

grader, the remaining portion of the mixture which passes through the second grader to the third grader and so on, until the batch of olives has been completely separated into 5 the desired number of grades; and a plurality of independent discharge troughs, each of which is associated with one of the graders and is accompanied by a discharge belt by means of which the different grades 10 of olives may be discharged from the side of the machine into a plurality of receptacles.

The supporting structure includes a number of connected units, each of which is provided 15 to support one of the graders and is of such height that the grading element which it supports, is arranged below the plane of the preceding grading elements.

The supporting structure for the first 20 grader, which member is designated generally by the letter A, consists of four corner posts 10, which are of equal height and receive a preferably rectangular frame 11, in which the grading rollers, grading cylinder, 25 discharge trough, and feeder belt are mounted, as will be presently explained. The corner posts 10 are mounted upon a pair of parallel sills 12 which latter members are of a length equal to the length of the entire machine, whereby they serve as supports for 30 the corners posts of all of the graders.

The supporting frame for the second grader, which member is generally designated by the letter B, includes two corner 35 posts 13 and a rectangular frame 14. The frame 14 is supported at its forward end on the upper terminals of the posts 13 and is secured by bolts or equivalent fastening devices to the forwardly located corner 40 posts 10.

The two remaining grading sections of the machine which are designated, as entireties in Fig. 1, by the letters C and D, are supported by pairs of posts 15 and 16 and 45 rectangular frames 17 and 18. The member 17 is secured at its rear end to the posts 13 and is mounted at its forward end upon the posts 15; while the frame 18 is secured to the posts 15 at its rear end and is mounted 50 at its forward end upon the upper ends of the posts 16.

It is now to be noted that the frames 11, 14, 17 and 18 are arranged in stepped relation to each other and that as a result, the 55 four graders A, B, C and D, which are mounted therein, are similarly related so that the unassorted olives after passing through the grader A may drop down to the feed belt and be carried forwardly by this 60 member for deposit upon the grader B and the unassorted olives which pass through the grader B may be carried forwardly and be deposited upon the grader C and so on until the mixture of olives has passed 65 through the entire machine.

Before proceeding with the detail description of the invention, I desire to particularly emphasize the fact that while the machine preferably includes four graders, or sections, as disclosed in the accompanying 70 drawings, it may without departing in any way from the spirit of the invention, consist in a less or greater number of graders. In this connection, it is to be explained that the present commercial practice is to grade 75 olives into four different sizes and that the preferred embodiment of my invention has, therefore, been designed to meet this requirement.

In taking up the detail description of the 80 grading mechanism, it is to be first explained that the four graders A, B, C and D are all substantially similar in construction and differ only in the extent to which the worms of the grading rollers are pitched 85 and the distance which the rollers are separated from the fixed cylinders, as will hereinafter become more apparent.

Referring now particularly to Fig. 1, it will be seen that the grader A includes a 90 cylinder 19, and a pair of rollers 20 and 21. The cylinder 19 is preferably formed from a length of brass tubing which is terminally mounted in the transverse bars 22 and 23 of the frame 11. The member 19 extends 95 longitudinally with respect to the machine and is centrally located within the frame 11. The rollers 20 and 21 are located on opposite sides of the cylinder and are disposed in parallel spaced relation thereto. 100 The two rollers are equi-distantly spaced from the cylinder, in order that all olives, except those of one size or grade, may pass down through the space between each roller and the cylinder. The terminals of the 105 rollers are provided with stub axles or trunnions 24, which members are journaled in bearings 25 mounted upon the bars 22 and 23.

The rollers 20 and 21 are similar in construction and are preferably formed from brass or metal tubing, although wood or a composition may be employed, if desired. Upon the face of each roller is formed a helical worm 26, as in Fig. 4. These worms constitute means whereby those olives which 115 are of too large a size to pass through the space between the rollers and the cylinders are moved forwardly and deposited in the discharge trough 27. Preferably the pitch of the helix described by each worm is equal 120 to the space between the cylinder 19 and the roller. It has been found that with this construction, less damage is done in the way of bruising and the like to the olives, than by any other construction of a similar nature.

The rollers are of considerably greater diameter than the cylinder 19 so that their upper surfaces lie in a plane considerably above the plane of the upper surface of the 130

cylinder, whereby they may constitute in connection with the cylinder, a trough so that the olives which are fed on the grader through the hopper E, will follow a true path and will not spill over the outer sides of the roller.

The discharge trough 27 extends transversely with respect to the machine and is, as best shown in Fig. 3, disposed below the frame 11, in position to receive the olives of the first grade which are carried forward by the rollers 20 and 21. Additional posts indicated at 28 are provided to support the terminals of the trough in connection with the posts 10.

Journaled between the posts 10 and 28, at each side of the machine, is a belt drum or roller 29. These members 29 are disposed with their axis of rotation slightly below the bottom wall of the trough 27 so that a continuous conveyer belt 30 which passes around the rollers may be operated across the upper face of the bottom wall of the trough. A drive pulley indicated at 31 is driven in a manner to be hereinafter described to actuate the belt, so that this member will cause the olives dropped into the trough 27, by means of the rollers 20 and 21, to move through the trough and out the side of the machine, as in Fig. 1 so that they may be discharged into any suitable receptacle placed beneath the discharge chute indicated at 32.

From the description thus far given, it will now be apparent that if a batch of olives is fed through the hopper E into the trough defined by the rollers 20 and 21 and the cylinder 19, which members constitute the first grading section A, the largest olives will be separated from the mixture and carried forwardly by the rollers to the discharge trough 27. Obviously, all those olives which are smaller than those of the first grade will pass down between the rollers and the cylinder and drop on to the feed belt.

In taking up the description of the feed belt, reference will now be had particularly to Fig. 3, wherein this belt is best shown in relation to all of the sections of the machine. The belt is driven from a wheel 33 which is mounted at the lower end of the machine and is driven by an electrical motor or equivalent power source. The lower portion of the belt passes directly to the rear end of the machine and about an idler drum or wheel 34 which is journaled in bearings 35 between the rearwardly disposed pair of posts 10. The wheel is so disposed that the belt, as it passes over the wheel, will travel as indicated at 36, in a horizontal plane, which is located immediately below the cylinder 19 and rollers 20 and 21. The portion 36 of the belt terminates beyond the rear end 35 of the grader B, being passed around an

idler wheel or drum 37 which is journaled between the forwardly disposed posts 10. Thus, it will be seen that those olives which fall through the spaces between the rollers 20 and 21 and the cylinder 19 will be carried forwardly by the portion 36 of the belt and deposited in the trough defined by the rollers 38 and 39 and cylinder 40 of the grader B.

It is now to be explained that the rollers and cylinder of the grader B, the discharge trough 41 and conveyer belt 42, associated therewith are all equivalent to the corresponding elements of the section A previously described. The rollers and cylinders, discharge trough and discharge belt of the sections C and D, are also similar to the corresponding elements of the section A. The only difference between the four graders is the pitch of the worm wires and the width of the space included between the different sets of rollers and their associated cylinders. In this connection, it is to be explained that the pitch of the worms of the rollers in the grader A and the space between these rollers and their accompanying cylinder is greater than the pitch of the worm and the space between the rollers and cylinders of the grader B. The worm and space between the rollers and cylinder of the grader C bears the same relation to the grader B as this member does to the grader A and the grader D bears a corresponding relation to the grader C.

When these olives which pass through the grader A are deposited upon the grader B, this member acts in the same manner as did the grader A to remove from the mixture of olives the next largest grade which is passed on to the discharge trough 41 and conveyed therefrom by the belt 42. The other olives which pass through the space between the rollers and cylinders of the grader B, are dropped on the portion 43 of the feeder belt. This member is, after passing over the belt wheel 37, rearwardly directed as at 44 and passed about a belt wheel 45 which is located in the rear of the belt wheel 37 and below the plane thereof. The portion 43 of the belt passes forwardly over a belt wheel 46 which is equivalent to the member 37 and then rearwardly directed over a belt wheel 47 which is related to the member 46, in the same manner as is the belt wheel 45 related to the belt wheel 37. The portion 43 of the belt serves to convey the olives which pass through the grader B on to the grader C.

After passing around the belt wheel 47, the belt is forwardly directed as at 49 and passes around a belt wheel 50, equivalent to the member 46 so that the portion 49 may convey the olives which drop through the grader C on to the grader D. The belt, after passing through the member 50 is rearwardly directed and passed around a belt

- wheel 51 and is then carried forwardly, as at 52 into the driven wheel or drum. The portion 52 obviously receives the olives and refuse which pass through the grader D.
- 5 A receptacle of any nature may be placed adjacent to the drive wheel 33 to receive this refuse and accompanying olives which will be all of too small a size to be commercially profitable.
- 10 It will now be noted that the portions 36, 43, 49 and 52 of the feed belt are all movable between pairs of longitudinally extending, parallel vertical walls 53 which, as shown best in Figs. 2 and 3, constitute troughs so 15 that the olives, being carried forward by the horizontal portions of the feed belt, may not spill over the sides thereof.
- Coming now to the description of the means employed in driving the worm rollers 20 and 21 of each of the grader sections A, B, C and D, the feed belt and the conveyer belts of the discharge troughs, reference will be had particularly to Figs. 1 and 5. As shown, the driving mechanism includes a 25 pair of parallel shafts 54 and 55 which extend longitudinally through the machine and are journaled at intermediate points in bearings 56 carried by the vertical posts 10, 28, 13, 15 and 16. These shafts are arranged 30 at the lower ends of the posts and are accompanied at their forward terminals, as in Figs. 3 and 5, by pinions 57 and 58, which are provided with helical teeth. These pinions 57 and 58 are adapted to mesh with the 35 worms 59 and 60 respectively which are keyed upon a horizontal jack shaft 61. The jack shaft 61 is provided at its outer end with a belt wheel 62, about which passes a belt 63. The belt 63 is connected to an 40 engine, motor or equivalent power source for driving the jack shaft. The driving wheel 33 of the feed belt is mounted at the approximate center of the jack shaft 61 and it will, therefore, be obvious that the feed 45 belt will be actuated when the shaft 61 is in operation. The stub axles at the rear ends of the worm rollers in each of the grading sections A, B, C and D are accompanied by pulley or belt wheels, as indicated at 64.
- 50 The members 64 of the rollers on the right-hand side of the cylinders in the several graders are connected by belts 65, as in Fig. 2, with belt wheels 66 which are mounted upon the shaft 54 at intermediate points.
- 55 The belt or pulley wheel 64 of the worm rollers on the left-hand side of the cylinders, in the several grader sections, are connected, as in Fig. 3, by belts 67 to the shaft 55 by means of belt wheels 68 which are keyed upon this member. The members 31 which, as previously stated, control the rollers at the right-hand ends of the discharge trough belts, are connected by belts 69 to the shaft 54 by means of a belt wheel 70, as in Fig. 1. It is now to be observed

that the worms 59 and 60 are oppositely wound so that the pinions 57 and 58 will rotate in opposite directions as indicated by arrows in Fig. 5. Thus the shafts 54 and 55 rotate in opposite directions and the left and right-hand rollers of each grader section, A, B, C and D, are rotated in opposite directions so that the worms of each will carry the olives forwardly through the grader section. It will also be noted that 75 since the shaft 54 turns to the left (as looked at from the rear end of the machine) the conveyer belts of the several discharge chutes will also be moved toward the left, to thereby move each grade of olives into the 80 discharge chutes 32.

In concluding the description of the drawings, I desire to explain that while the rollers and cylinders of each section are shown as being relatively short in proportion to 85 the width of the machine, such disclosure has been made only because of the necessity of restricting the views to the given space upon the sheets. In the actual construction of the machine, the rollers and cylinders are 90 of considerable length so that the olives will have ample opportunity to pass between the rollers and the associated cylinder, if they are smaller than the grade which the particular section through which they are 95 passing is intended to separate from the mixture.

In reduction to practice, it has been found that the form of this invention illustrated in the drawings and referred to in the above 100 description as the preferred embodiment is the most efficient and practical; yet realizing that the conditions concurrent with the adoption of this device will necessarily vary, it is desirable to emphasize the fact 105 that various minor changes in the details of construction, proportion and arrangement of parts may be resorted to, when required, without sacrificing any of the advantages 110 of this invention, as defined by the appended claims.

What is claimed is:—

1. A grader including a plurality of grading sections, each adapted to remove from a mixture of material one constituent thereof, 115 each of said grading sections including a cylinder, and a pair of worm rollers journaled on opposite sides of the cylinder and disposed with their axes above the axis of the cylinder whereby to constitute a trough 120 within which the material may be carried.

2. In a grader, a cylinder, a pair of oppositely rotatable rollers journaled on opposite sides of the cylinder and disposed with their axes above the axis of the cylinder 125 whereby to constitute a trough, and means for causing the material disposed in said trough to be fed longitudinally along said trough.

3. A grader including a plurality of grad- 130

ing sections, each adapted to remove from a mixture of material one constituent thereof, each of said grading sections including a cylinder, a pair of worm rollers journaled 5 on opposite sides of the cylinder, means for conveying the material which drops through the spaces between the rollers and cylinder on to the rollers and cylinder of the next adjacent grading section, and means for 10 conveying from the machine that constituent of the mixture which is removed by each grading element.

4. A fruit grader including a plurality of 15 grading sections arranged in stepped relation to each other, the first of said sections being at the greatest elevation and the last of said sections being at the lowest elevation, each of said sections being adapted to remove from the mixture of fruit one grade of 20 fruit, and a continuous conveyer belt having its upper flight disposed in stepped planes, each extending beneath and extending along the entire length of one of said grading sections and at its discharge end extending 25 over the next grading section below.

5. A fruit grader including a plurality of 30 grading sections arranged in stepped relation to each other, the first of said sections being at the greatest elevation and the last 35 of said sections being at the lowest elevation, each of said sections being adapted to remove from the mixture of fruit one grade thereof, and means for conveying fruit from one section to the other comprising a continuous belt, a belt wheel disposed at the entrance end of all of said grading sections except the first one, and over which the conveyer successively passes, and a plurality of 40 belt wheels each disposed rearward of a corresponding first named belt wheel and on a lower level than the corresponding first named belt wheel and over which said conveyer passes whereby to cause the upper flight of the conveyer belt to be arranged in 45 downwardly stepped planes, each plane of the belt discharging upon the entrance end of one of the grading sections, the conveyer then extending rearward and downward over the second named belt wheel and then 50 extending below the next successive grading section and along its entire length.

6. An olive grader including a plurality of 55 grading sections arranged in stepped relation to each other, the first of said sections being of the greatest elevation and the last of said sections being at the lowest ele-

vation, each of said sections being adapted to remove from the mixture of olives one grade of olives, a discharge trough for each grading section to receive the olives removed 60 by this section, a belt mounted in each trough for conveying the olives therefrom, and a conveyer belt mounted to receive from each grader section those olives which pass through the section and to carry them forwardly and to deposit them upon the next adjacent section.

7. An olive grader including a plurality of 70 grading sections, a supporting frame for the sections, said sections being disposed in stepped relation to each other, the first of said sections being arranged at the greatest elevation, each of said grading sections including a relatively fixed longitudinally disposed cylinder, and a longitudinally extending worm roller arranged upon each side of said cylinder in parallel spaced relation thereto, a transversely arranged discharge belt mounted at the forward end of each 75 grader section to receive from the rollers thereof that grade of olives which is removed by the section, and a continuous feed belt passing beneath the grader sections and extending at intermediate points over the rear end of each section, whereby the belt 80 receives from each section those olives which pass through the section and carries said olives on to the next adjacent grader section.

8. An olive grader including a plurality of 85 independent grading sections arranged in 90 stepped relation to each other, the first of said sections being arranged at the greatest elevation, each of said sections including a relatively fixed cylinder, and worm rollers arranged on each side thereof, said rollers 95 being spaced from the cylinder a distance slightly less than the smallest dimension of the olives of the size which the section is to remove from the mixture, a discharge belt receiving the olives removed by each grader 100 section for conveying them from the machine, and a feed belt mounted to receive the olives which pass through each grading section and to convey them on to the next adjacent grader section.

105 In testimony whereof I hereunto affix my signature in the presence of two witnesses.

WILLIAM D. MACKRILL.
